ATTY.

UNITED STATES PATENT OFFICE.

EUSTACE CREEES AND CHARLES S. COURT, OF PROVIDENCE, RHODE ISLAND,
ASSIGNORS TO WILLIAM BENS, OF SAME PLACE.

DESIGN FOR A HANDLE FOR BUTTON-HOOKS OR SIMILAR ARTICLES.

SPECIFICATION forming part of Design No. 31,274, dated July 25, 1899.

Application filed June 30, 1899. Serial No. 722,471. Term of patent 3½ years.

To all whom it may concern:

Be it known that we, EUSTACE CREEES and CHARLES S. COURT, citizens of the United States, residing at Providence, in the State of Rhode Island, have invented and produced a new and original Design for the Handle of a Button-Hook or Similar Article, of which the following is a specification, reference being had to the accompanying drawing, forming a part thereof.

The drawing shows a view of one of the sides of the handle of a button-hook provided with our new and original design, the same design being formed upon both sides of the handle.

The leading or material features of our design consist in the circular bead *a*, from which are extended the opposite foliated scrolls *b b*, which are turned inwardly at their terminal ends *c c* and also at their intermediate points *d d*, the ornament *e*, the branching foliated

scroll *f*, the reversely-foliated scrolls *g g* and the panel *h*, the reversely-foliated scrolls *i i*, the reversely-foliated scrolls *j j* and the panel *k*, the floral ornament *l*, the reversely-foliated scrolls *m n m n*, the reversely-foliated scrolls *o o* and *p p*, the panel *q*, and the terminal ornament *r*.

It is apparent that this design for the handles of button-hooks is adapted for the handles of similar articles.

Having now described our new design, what we claim as new, and desire to secure by Letters Patent, is—

The design for the handle of a button-hook or similar article, as herein shown and described.

EUSTACE CREEES.
CHAS. S. COURT.
